(57) **CLAIM**

I claim the ornamental design for a product container, as substantially shown and described.

DESCRIPTION

FIG. 1 is a front view of the product container shown in an attached configuration.

FIG. 2 is a back view thereof.

FIG. 3 is a left side view thereof.

FIG. 4 is a right side view thereof.

FIG. 5 is a top plan view thereof.

FIG. 6 is a bottom plan view thereof.

FIG. 7 is a perspective view thereof.

FIG. 8 is a front view of the container shown without the lid to show the inner structure of the product container that is not visible when the lid is shown in the attached configuration.

FIG. 9 is a back view thereof.

FIG. 10 is a left side view thereof.

FIG. 11 is a right side view thereof.

FIG. 12 is a top plan view thereof.

FIG. 13 is a bottom plan view thereof.

FIG. 14 is a perspective view thereof.

FIG. 15 is a front view of the lid shown without the container to show the inner structure of the lid that is not visible when the lid is shown in the attached configuration.

FIG. 16 is a back view thereof.

FIG. 17 is a left side view thereof.

FIG. 18 is a right side view thereof.

FIG. 19 is a top plan view thereof.

FIG. 20 is a bottom plan view thereof; and,

FIG. 21 is a perspective view thereof.

The broken lines show portions of the product container and surface details that form no part of the claimed design.

1 Claim, 10 Drawing Sheets
